UNITED STATES PATENT OFFICE

2,513,623

PORTABLE BASEBALL, SOFTBALL
SCOREBOARDLawrence L. Bray, Sheboygan, Wis., assignor to
Sporco, Inc., Milwaukee, Wis., a corporation of
Wisconsin

Application December 17, 1947, Serial No. 792,158

2 Claims. (Cl. 177—384)

1

This invention relates to a portable scoreboard that may be used to indicate the score in games of sport such as soft-ball, baseball, regular baseball or games of similar character.

An object of the invention is to provide a scoreboard that is of a size to be plainly visible from the entire ball playing field.

Another object of the invention is to provide a compact scoreboard that is self-contained, that is, it carries its own source of illumination and a current source for the energizing of the illuminating means.

Another object of the invention is to provide a scoreboard that is susceptible of being reduced in size to conserve space and to protect the board from damage or pilferage.

The scoreboard is susceptible of being transported with little effort, so that it can be placed at the most desired location on the playing field and the grounds adjacent the playing field.

With the above and other objects and advantages in view, the invention consists of the novel details of construction, arrangement and combination of parts more fully hereinafter described, claimed and illustrated in the accompanying drawings in which:

Figure 1 is a front elevational view of an embodiment of the invention;

Figure 2 is a rear view of Figure 1;

Figure 3 is a rear view of Figure 1;

Figure 4 is an end view of Figure 1;

Figure 5 is a vertical, sectional view on the line 5—5 of Figure 1;

Figure 6 is an elevational view of the device in folded position;

Figure 7 is a rear view of Figure 6;

Figure 8 is an end view of Figure 6;

Figure 9 is a plan view of the panel and lights mounted thereon;

Figure 10 is an elevational view of one of the score indicating means and

Figure 11 is a diagrammatic view of the circuit of the device.

Referring more in detail to the drawings, the reference numeral 20 is used to generally designate the scoreboard embodying the invention.

The scoreboard 20 comprises a base 21 to which is fixed the axle supports 22 for the axles 23, on which are mounted in the conventional manner, the ground engaging wheels 24. A tow bar 25 or handle 25 connected to the front support 22 permits the scoreboard to be towed from location to location.

Along the front longitudinal edge of the base 21 is fixed the vertically disposed lower panel 58

26, and hinged to the upper longitudinal edge of the panel 26, by hinges 27, is the upper vertical disposed panel 28.

Hinged to each vertical edge of the panel 28 by hinges 29 are the wing panels 30 and 31 respectively. Triangular brace panels 32 are fixed to the ends of the base, and the ends of the panel 26 to retain the panel 26 in fixed vertical relation to the base 21.

10 To retain the panel 28 in its vertical position, bars 33 removably seated in sockets 33' in the base 21 are used. The bars have hooked ends 34 that engage in the screw 35 fixed in the upper longitudinal edge of the panel 28. The panels 31 and 30 and each brace panel 32 is provided with apertured brackets 36 to receive the bent ends of the brace bars 37, whereby the wing panels are retained in the same vertical plane with the panel 28.

15 The wing panel 30 and a portion of the panel 28 support removable panels 38, which indicate the names of the teams participating in the game. The remainder of the panel 28 and wing panel 31 are divided into box-like spaces 39 which are provided with openings 40 to receive bolts 41, whereby the score plates 42 may be supported in each box. Above the box, the panels 28 and 31 are provided with means for indicating the number of each box, as shown at

20 43. Secured to the rear of the panel 21, is the panel or plate 44, carrying the bulb socket 45 for the bulbs 46. The turned flanged ends 47 of the panel 44 contact the rear of the panel 21, to receive the portion 48, whereby the panel 44 is removably secured to the panel 21. Openings 50 are provided in the panel 21 to permit the bulbs to be visible through the panel.

25 Leaves 51 are hinged to the face of the panel 26 by hinges 52, and when the leaves are in vertical position, they close the openings 50. When the leaves are retained in horizontal relation to the panel 21 by brace bars 53, the bulbs will be visible through the openings 50. One set of bulbs is used for balls—another set for strikes;

30 a set for out and one each for hits and errors, as can be seen from the drawings. The bulbs used are also of different colors to distinguish one from each other. For example, amber lights for balls, blue lights for strikes, red lights for outs, an amber light for hit and a red light for error.

35 In Figure 11, there is shown the diagrammatic view of the circuit for the lights including the storage battery 54 which is fixed on the base 21. The main current lines 55 and 56 are connected

in parallel to the sockets 45 for the bulbs 46, and a switch 57 is interpolated in the wires for the sockets to control each individual bulb.

The switches 57 are fixed to a switchboard 58 fixed to one of the panels 32, so that each bulb can be individually controlled by the switchboard 58.

In use, the opposite panels 38 are mounted in place as shown in Figure 1. The switches 57 are open unless it is desired to close the switch to indicate a ball, strike, out, hit or error. The score plates 42 are hung in place by means of the bolts 41, according to the runs scored.

To move or store the scoreboard, the leaves 51 are lowered to protect the bulbs. Panels 38 and score plates 42 are removed and placed on the base 41. The bars 37 are removed, permitting the panels 39 and 31 to be swung into contact with the panels 28.

The bars 33 are removed from the sockets 33', their hooked ends are removed from the screw eyes 35 and the panel 28 is swung downward as shown in Figure 8.

Hasps 59 fixed to the rear longitudinal edge of the base 21 are then swung upwardly to receive the screw eyes 35, and a pin 60 or a lock (not shown) is used to retain the panel in closed position. The panel 28 then with the panels 32 forms a box-like structure which protects the wiring storage battery and wiring from damage or pilferage.

There has thus been provided a scoreboard that is portable, compact and will readily accomplish the purpose for which it is designed.

It is believed that from the foregoing description, the combination and use of the scoreboard will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. A portable scoreboard comprising, a transportable box like structure having a rigid front wall, an upwardly swingable plate forming a closure for said structure when not in use, lateral extensions on opposite ends of said plate, said extensions being foldable inwardly against said

plate, illuminating means visible through said front wall for indicating variable conditions of play, a current source for said illuminating means housed within said structure, controlling means for said illuminating means, means for supporting said plate in approximately upright position above said front wall when the scoreboard is in use, means for supporting said extensions in laterally extended position when the scoreboard is in use, and score indicating means cooperable with said plate and said extensions to present a score to view in conjunction with said illuminating means when said plate is swung upwardly, said score indicating means being confinable within said structure when said plate is used as a closure.

2. A portable scoreboard comprising a transportable box like structure having a rigid front wall, an upwardly swingable plate forming a closure for said structure when not in use, a lateral extension foldable inwardly against said plate, illuminating means visible through said front wall for indicating variable conditions of play, a current source for said illuminating means housed within said structure, controlling means for said illuminating means, means for supporting said plate in approximately upright position above said front wall when the scoreboard is in use, means for supporting said extension in laterally extended position when the scoreboard is in use, and score indicating means cooperable with said plate and said extension to present a score to view in conjunction with said illuminating means when said plate is swung upwardly, said score indicating means being confinable within said structure when said plate is used as a closure.
